GRINDING MACHINE

Frederick S. Haas, Cincinnati, Ohio, assignor to
 Cincinnati Grinders Incorporated, Cincinnati,
 Ohio, a corporation of Ohio

Application January 29, 1932, Serial No. 589,698

4 Claims. (Cl. 125—11)

This invention relates to improvements in machine tools and especially to improvements in grinding machine structures.

An object of the invention is the provision of an improved mechanism adapted for cambering or crowning the operative face of a grinding wheel, which is particularly adapted for grinding the crown or camber on large rolls such as used in rolling mills.

19 A further object of the invention is the provision of a simple, inexpensive mechanism that may be readily mounted on existing portions of grinding machines for accomplishing the above noted object.

15 An additional object of the invention is the provision of improved means for adjusting the said wheel trimming or truing mechanism to obtain various radii of contour on the work.

Other objects and advantages of the present 20 invention should be readily apparent by reference to the following specification considered in conjunction with the accompanying drawings forming a part thereof, and it is to be understood that any modifications may be made in the exact 25 structural details there shown and described, within the scope of the appended claims, without departing from or exceeding the spirit of the invention.

In the drawings:

30 Figure 1 is a front elevation of a grinding machine embodying the improvements of this invention.

Figure 2 is a view taken substantially on line 2—2 of Figure 1, showing a portion of the machine 35 in elevation and other portions in cross section.

Figure 3 is a fragmentary sectional view taken on line 3—3 of Figure 2.

Figure 4 is an end elevational view of the truing element and parts supporting it as seen particularly from line 4—4 of Figure 2.

Figure 5 is a fragmentary sectional view taken on line 5—5 of Figure 2.

Figure 6 is a fragmentary sectional view taken on line 6—6 of Figure 2.

45 Figure 7 is a view partly in section and partly in elevation as seen particularly from line 7—7 of Figure 2.

Throughout the several views of the drawings similar reference characters are employed to denote the same or similar parts.

Large rolls such as those used in rolling mills are frequently provided with a slight camber or crown which extends from one end of the roll to the other. In the production of these rolls the 55 grinding wheel is actuated toward and from the

axial center of the work during its axial travel past the wheel. For providing the desired finish on the rolls, resort is had to an oppositely contoured grinding wheel which effectively eliminates a spiral track which would result if a plain faced wheel were used. It is understood that the crown on the wheel is of a considerable radius since it need be only sufficient to prevent the corner of the wheel from digging into the work as it is traversed thereby. Accordingly, considerable 60 difficulty was experienced in producing a mechanism of sufficient compactness and simplicity to be mounted on the machine for accomplishing this result. These difficulties and inconveniences have been obviated by the mechanism disclosed in the 65 drawings.

A machine for grinding the rolls comprises a bed 10 having formed on the upper face thereof guideways 11 for a translatable table 12 mounted thereon. The table 12 has secured to it near its 70 opposite ends a head stock 13 and a tail stock 14, from which respectively project centers 15 and 16 which centralize the work as respects the grinding wheel. The table 12 is further provided with journaled rests 17 and 18 respectively engaging 75 the opposed journal bearings 19 of the work 20. The body of the roll 20 is located between the journals 19 and it is this portion that is adapted to be produced with a camber or crown. The work is suitably dogged as at 21 with the head 80 stock 13 whereby it is rotated through the prime mover or motor 22 secured to the head stock 13. The table 12 is adapted to be translated either manually by means of hand wheel 23 or by power 85 in the usual manner, which power means is 90 reversible through the reversing lever 24.

Mounted on the bed for movement transversely thereof toward and from the table 12 is a spindle carriage which has secured to it a guard 25. This guard 25 encloses a grinding wheel 26 secured to 95 the spindle of the carriage and through the rotation of the spindle, the wheel is properly rotated. Any desirable means may be employed for effecting the in and out movement of the grinding wheel 100 during the travel of the work past the wheel.

As shown in Figure 3, the tail stock center 16 is provided with the usual taper and is received in a correspondingly tapered socket 27 formed in the forward end of the tail stock spindle 28 adapted to be axially adjusted relative to the tail stock 105 housing 29. The housing 29 terminates in a cylindrical barrel portion 30 in which the spindle is mounted for axial movement relative thereto. At the forward end of the barrel 30 it is provided with a reduced sleeve-like portion 31 encircled in 110

actual practice by a flange 32 of cup shaped cap 33. This cap 33 is secured by means of screws or bolts 34 to the forward end of the spindle 29 and is movable with said spindle during its axial adjustment.

The truing or grinding attachment forming the subject of this invention is carried by or secured to this cup shaped cap 33 and for which purpose the cap has formed therein a locating notch or 10 pocket 35 receiving a pin 36. The pin 36 is secured in a ring like bracket 37 which entirely surrounds the cap 33. The bracket 37 has integral therewith a sleeve-like or tubular portion 38 which extends in a direction parallel with the 15 general horizontal axis of the machine. The ring-like bracket 37 is further provided with a boss 39 having threaded therein a screw 40 operated by the integral knob or handle 41. The inner end of the screw 40 actuates a clamping shoe 20 42 which engages with the outer surface of the cap 33 for clamping the bracket 37 in its desired position.

Rotatably journaled in the sleeve or bearing portion 38 is a shaft 43 journaled in bushings 44 25 pressed into the sleeve 38. The outer end of the shaft 43 terminates in a flange portion 45 while the inner end of the said shaft has a reduced portion 46 integral therewith. The flanged portion 45 is under cut to provide an internal gear 47 30 meshing with the teeth of pinion 48, which is mounted on the eccentric portion 49 of a headed stud 50. The teeth of the pinion 48 are also intermeshed with internal gear teeth 51 formed within a bracket 52 which has a flange 53 abutting 35 a similar flange 54 formed on one end of the sleeve 38. Clamping screws 55 are provided which extend through the flanges 53 and 54 for securing the bracket 52 to the bearing or sleeve 38. The headed stud 50 has integral therewith 40 a body portion 56 which is journaled in the bracket 52 so that its axis is co-incident with the axis of the shaft 53 when mounted in operative position. A reduced portion 57 extends from the body portion 56 to which is secured a hand 45 wheel 58 whereby the said stud 50 is rotated. It should be noted that the internal gears 47 and 51 are of the same pitch but that there is a different number of teeth in each gear, preferably a single tooth differential existing between them, 50 so that these gears together with the pinion 48 constitute a planetary gear system for rotating the shaft 43 at a very slow rate compared to the rotation of the headed stud 50.

The sleeve or bearing 38 terminates in a hood 55 or guard 59 which encloses the reduced end 46 of the shaft 43. Secured to this reduced portion of the shaft is an arm 60 having formed in its lower end a guideway 61 receiving a block 62. Extending through the arm and communicating 60 with the guideway 61 is an elongated perforation 63 through which a bolt 64 projects having its threaded portion received in the block 62 and clamping the said block in adjusted positions thereby. The block 62 is further provided with 65 a perforation receiving a diamond or other truing tool holder 65 which is clamped in position therein by means of a set screw or the like 66. To properly adjust the block 62 relative to the arm 60, it is provided with suitable graduations 70 67 co-operating with a fixed point 68 carried by the arm 66 adjacent the guideway 61. In order to prevent moisture or coolant from entering the bearings 44, the hood 59 has secured to it a plate or guard 69, thereby completely enclosing the end 75 46 of the shaft 43.

The operation of the mechanism is as follows. The table 12 is actuated relative to the bed 10 to align the horizontal axis of the shaft 43 with the vertical axis or center of the wheel. The diamond 65 was previously adjusted relative to the arm 60 to the proper position below the plane of the horizontal center of the wheel depending on the amount of camber or crown desired to be formed on the wheel. The grinding wheel is then fed toward the table to engage the diamond or truing tool with one corner of the grinding wheel at the point below the plane of the horizontal center thereof. The hand wheel 58 is then rotated for actuating the arm 60 through a vertical plane, which due to its position relative to the grinding wheel effects an arcuate movement as respects the active face thereof. After each pass of the diamond across the face of the wheel, the wheel is fed in the desired amount for the next pass of the tool relative thereto. This continues until the desired crown or camber is provided on the wheel. The planetary gear mechanism including the pinion 48 and internal gears 51 and 47 effects a very slow uniform movement of the diamond relative to the wheel so that a true face 100 is formed on the grinding wheel.

In order to prevent the arm 60 falling by gravity to a horizontal position and to hold the said arm in any desired angular position, the sleeve or bearing portion 38 is provided near the flange 105 54 with a pair of sockets 70 and 71 in each of which is mounted a spring 72 abutting on one end with a plug 73 and on the other end with friction drag shoes 74. The other end of the shoes 74 is held in frictional engagement with the flange 45 and effectively holds the said flange to prevent inadvertent rotation thereof.

What is claimed is:

1. In a truing device of the class described for crowning the operative face of a circular wheel 115 the combination with a bed rotatably supporting the wheel, of a rotatable shaft having its axis disposed at right angles to the axis of the wheel, an arm carried by the shaft for movement therewith through a plane parallel with a tangent of the 120 wheel, a resurfacing tool carried by the arm for movement therewith through a plane parallel with the tangent, but which plane is disposed between the tangent and the axis of the wheel and whereby oscillation of the truing tool provides a 125 crown on the surface of the wheel, and means for adjusting the truing tool in its plane of movement toward and from the axis of the shaft to vary the crown produced on the wheel.

2. In a truing device of the class described for 130 crowning the operative face of a circular wheel the combination with a bed rotatably supporting the wheel, of a rotatable shaft having its axis disposed at right angles to the axis of the wheel, an arm carried by the shaft for movement there- 135 with through a plane parallel with a tangent of the wheel, a resurfacing tool carried by the arm for movement therewith through a plane parallel with the tangent but which plane is disposed between the tangent and the axis of the wheel and 140 whereby oscillation of the truing tool provides a crown on the surface of the wheel, and means for adjusting the truing tool in its plane of movement toward and from the axis of the shaft to vary the crown produced on the wheel, said adjusting 145 means comprising a block supporting the tool, and clamping and guiding means carried by the arm for the block.

3. In a truing device of the class described the combination with a bed for rotatably supporting 150

a circular grinding wheel adapted to have its operative surface crowned, of a tail stock supported by the bed adjacent the operative face of the grinding wheel, a bracket secured to the tail stock, a shaft oscillatably journaled in the bracket having its axis at right angles to the axis of the grinding wheel, the axes of the grinding wheel and shaft lying in spaced parallel planes, a truing tool carried by the shaft and oscillatable there-
5 with through a plane normal to the parallel planes of the axes of the wheel and shaft but contacting with the wheel at a point lying outside of the plane of the wheel axis above referred to, and means for adjusting the position of the truing tool as respects the plane of the wheel axis.
10 4. In a truing device of the class described the combination with a bed for rotatably supporting a circular grinding wheel adapted to have its
15 operative surface crowned, of a tail stock sup-
ported by the bed adjacent the operative face of the grinding wheel, a bracket secured to the tail stock, a shaft oscillatably journaled in the bracket having its axis at right angles to the axis of the grinding wheel, the axes of the grinding wheel and shaft lying in spaced parallel planes, a truing tool carried by the shaft and oscillatable there-
20 with through a plane normal to the parallel planes of the axes of the wheel and shaft but contacting with the wheel at a point lying outside of the plane of the wheel axis above referred to, means for adjusting the position of the truing tool as respects the plane of the wheel axis, and rotary means carried by the bracket for effecting the slow steady oscillatory movement of the shaft and truing tool.
